CORNER STUD CONSTRUCTION

Harry Holdsworth, Warren Point, N. J.

Application July 17, 1941, Serial No. 402,738

5. Claims. (Cl. 72—121)

The present invention relates to a building construction and to a corner bead used therein.

The invention is more specifically concerned with a building construction including two wall structures which join each other at an angle, so as to form a corner, where each wall is provided with a plaster-receiving member, the floor and ceiling between which the walls extend having plates affixed thereto which determine the position of the corner, and a corner bead extending from floor to ceiling and secured to the floor and ceiling plates, with means carried by the corner bead for retaining the plaster-receiving means in position.

The invention further contemplates a corner bead for use with plastered walls at a corner where the bead includes a sheet of metal doubled on itself to form an elongated nose, with two spaced apart legs and an intermediate fold between each leg and the nose. The fold serves not only the function of positioning the plaster-receiving means but also enables a nail-like element to be passed through the fold to hold the plaster-receiving means.

The principal object of the invention is to provide a corner construction in which once the corner positioning plates are located at the floor and ceiling, the corner bead may be attached to the parts accurately without the use of levelling devices or a plumb line.

Another important object of the invention is the provision of a corner bead which will serve the function of a stud extending between the floor and ceiling so as to contribute material support not only to the wall as such but to the plaster-receiving means which is a part of the wall.

Other objects and advantages will appear as the description proceeds and with reference to the accompanying drawings, in which—

Fig. 1 is a perspective detail showing the manner of attaching the corner bead to a plate;

Fig. 2 is a sectional plan of a corner construction embodying the present invention;

Fig. 3 is a view along the line 3—3 of Fig. 2; and

Fig. 4 is a perspective detail of a plate member.

Referring now with particularity to the embodiment illustrated, two wall assemblies are shown approaching each other at an angle to form a corner.

Each wall preferably, though not necessarily, includes ceiling and floor members 1 (the floor member only being shown), attached thereto having a flange 2 and ears 3 bent inwardly therefrom towards each other. A similar member is

provided on the ceiling, these two members determining accurately the position of the final wall. Studs are shown at 4 preferably formed of a length of sheet metal folded upon itself to form a forwardly projecting nose 5 and two oppositely extending base portions 6. As shown, the studs are intended to be located with respect to the floor and ceiling members so that the ears 3 overlie the base portion 6 and thus hold the studs in position.

It is to be noted that the nose 5 of the studs extends outwardly a sufficient distance so that the plaster carrying member 7 may overlie the ears 3 and a base portion 6 in substantial abutment with the nose 5. Such plaster carrying member may be plasterboard, wall board, cellulosic board composition, expanded metal lath or the like or in fact any member ordinarily used as a base for carrying wall plaster.

A nail-like element 8 may then be passed through aligned apertures in the nose 5 to hold the plaster-carrying member 7 in position.

The above construction is described in detail in my copending application Serial No. 328,840, filed April 10, 1940. The walls having thus been accurately positioned as above indicated, a corner plate having a front wall 9 and a securing flange 10 is fastened to the ceiling and a corresponding element to the floor at the location which the corner is to occupy. As shown in Fig. 2, the front wall 9 of the plates is located so that the plaster-carrying member 7 may lie closely against the same and in alignment therewith.

The particular corner bead which is an important part of my invention comprises a length of sheet metal folded on itself so as to form an elongated nose 11 with an enlargement 12, the other end portion of the corner bead terminating in two spaced apart legs 13 with an intermediate fold between each leg and the nose, the fold comprising the walls 14 and 15. As shown, the wall 15 lies substantially at right angles to the leg 13, the whole being so positioned that the end of a plaster-carrying member 7 will substantially abut the same.

Each leg 13 is provided with a series of perforations 16 adapted to receive an ear 17 projecting outwardly from the front wall 9 of the floor and ceiling plates, the ear being then bent over to secure the corner bead in place.

Thus the corner bead extends completely between floor and ceiling and is secured to the floor and ceiling plates so that the bead in effect performs the function of a stud, not only rigidly connecting the floor and ceiling plates but accu-

rately positioning the corner of the wall without the use of leveling devices or a plumb line.

When, therefore, a suitable length of plaster-carrying member 7 is placed in position between the nearest stud 4 and the wall 5 of the fold in the corner bead, a nail-like element 18 may then be passed through aligned apertures in the walls 14 and 15 of the fold and even extended into a wall of the nose 11. Thus, the plaster-carrying member is firmly and accurately held in its proper position with regard to the remainder of the assembly.

It is desirable, of course, that the main body of the corner bead be perforated so that when plaster is applied, say to the line 19, not only is the bead completely covered therewith but the plaster may be forced into the perforations and enter the inside of the bead proper. This makes for better stability.

Plaster may then be applied to the other face of the plaster-carrying member 7, say to the line 20, thus producing a finished plastered wall.

It is to be understood, of course, that the corner bead may be made of any desirable material in suitable weights, either integrally formed or of assembled parts.

The perforations to receive the ears 17 and the nails 18 may be standardized so as to facilitate the universal application of the construction to various building conditions, which avoids the necessity of special construction for each job.

Such a combination is particularly desirable in that it not only permits of the formation of a wall with an equal quantity or thickness on each side of the plaster-carrying member but permits of the erection of such a construction in a minimum length of time without plumbing.

While the invention has been shown and described with particular reference to specific embodiments, it is to be understood that it is not to be limited thereto but is to be construed broadly and restricted solely by the scope of the appended claims.

I claim:

1. A building construction including two wall structures joining each other at an angle so as to form a corner, each wall including a plaster receiving member, a floor plate and a ceiling

plate affixed to a floor and ceiling respectively, said plates determining the position of the corner, a corner bead extending from floor to ceiling and secured to the floor and ceiling plates, and means carried by the corner bead for retaining the plaster-receiving means in position in which the corner bead is provided with a fold, a portion of which projects outwardly beyond the outer face of the plaster-receiving member, the plaster-receiving member retaining means penetrating said portion of said fold.

2. A building construction including two wall structures joining each other at an angle so as to form a corner, each wall including a plaster receiving member, a floor plate and a ceiling plate affixed to a floor and ceiling respectively, said plates determining the position of the corner, a corner bead extending from floor to ceiling and secured to the floor and ceiling plates, and means carried by the corner bead for retaining the plaster-receiving means in position in which the corner bead is provided with an elongated nose, angularly extending legs and a folded portion between the nose and each leg, the plaster-receiving member in each wall having an end portion overlying a leg and adjacent a fold, the plaster-receiving member retaining means comprising a nail-like element penetrating the folded portion of the corner bead and engaging the plaster-receiving member.

3. A corner bead for use with plastered walls comprising a sheet of metal doubled on itself to form an elongated nose, two spaced apart legs and an intermediate fold between each leg and the nose, said legs forming an abutment for plaster receiving members and said folds having means to receive retaining means to hold said plaster receiving members in place.

4. The corner bead of claim 3 in which that portion of the fold adjacent each leg is substantially at right angles to the leg.

5. The corner bead of claim 3 with aligned perforations in each side of the folded portions and adapted to receive nail means for retaining plaster-receiving means in place when the wall is erected.

HARRY HOLDSWORTH.
